COMBINED LOUD SPEAKER AND ILLUMINABLE DISPLAY SIGN UNIT

Stanley Joseloff, Westport, Conn.

Application January 8, 1958, Serial No. 49,170

Term of patent 14 years

(Cl. D1—12)

Figure 1 is a perspective view of a combined loud speaker and illuminable display sign unit showing my new design;

I claim:

The ornamental design for a combined loud speaker and illuminable display sign unit, substantially as shown and described.
